UNITED STATES PATENT OFFICE.

OTTO HERMAN ROESSLING, OF PHILADELPHIA, PENNSYLVANIA, ASSIGNOR TO CHARLES BECK COMPANY, OF PHILADELPHIA, PENNSYLVANIA, A FIRM COMPRISING CHARLES BECK, CHARLES J. BECK, A. S. BECK, H. P. BECK, LEONIDAS BECK, AND ANDREW SIMON.

MACHINE FOR MAKING PAPER TUBES.

1,271,370.

Specification of Letters Patent. Patented July 2, 1918.

Application filed January 19, 1918. Serial No. 212,729.

To all whom it may concern:

Be it known that I, OTTO HERMAN ROESSLING, a subject of the King of Belgium, (having declared my intention of becoming a citizen of the United States,) and a resident of Philadelphia, county of Philadelphia, State of Pennsylvania, have invented certain Improvements in Machines for Making Paper Tubes, of which the following is

10 a specification.

My invention relates to certain improvements in machines for manufacturing paper tubes.

One object of my invention is to manufacture endless paper tubes from flat strips of material fed lengthwise into the forming mechanism.

A further object of the invention is to provide means for securing the several layers 20 of paper forming the tube so that one section will be held firmly to another and to make a cylindrical tube by a continuous operation.

The invention also relates to details of the 25 mechanism which will be fully described hereinafter.

In the accompanying drawings:

Figure 1^a is a plan view of the roll portion of the machine on the line 1—1, Fig. 2; 30 Fig. 1^b is a plan view of the machine showing the reels and the pasting mechanism;

Fig. 2 is a side view of the roll section of the machine;

Fig. 3 is a transverse sectional view on the line 3—3, Fig. 2;

Fig. 4 is an enlarged sectional view showing the pairs of rolls;

Fig. 5 is an end view showing two pairs 40 of rolls and the tube in section;

Fig. 6 is a detached perspective view showing the mandrel on which the roll is formed;

Fig. 7 is a perspective view showing the method of forming the strips of paper in the 45 tube;

Fig. 8 is a sectional view of the finished tube, showing the joints; and.

Figs. 9 and 10 are detached views of the sizing die.

50 By my improved machine, tubes are formed from strips of paper fed from reels and they are bent longitudinally by means of the formers to produce a tube. Paste, or

other adhesive material, is applied to two of the strips when a three-ply tube is 55 formed, so that the paste will be between the several strips. The rolls, which finish the tube, are driven continuously, while the mandrel, on which the tube is formed, is reciprocated. The mandrel has reduced portions and is yieldingly held so that the tube will be pinched between the rolls and the shoulder on the mandrel which causes the mandrel to move forward until the rolls are opposite the reduced portion of the mandrel, 65 when a spring will retract the mandrel, leaving the tube in the forward position. Thus the tube has an intermittent forward movement. The construction of the machine by which this is accomplished is the main feature of the invention.

Referring to the drawings, 1 is the base of the machine, suitably supported, and on one end of the machine is a platform 2 carrying three reels 3, 4 and 5, mounted in suitable bearings 6. The paper, which eventually forms the tube, is wound on these reels and is fed from these reels to the formers 7, 8 and 9 respectively. In order to apply paste, or other cementitious material to secure the several thicknesses of paper together, I provide an apparatus 10 having rolls 11 and 12, and the two side strips of paper passing from the reels 4 and 5 pass through the pasting apparatus and paste is 85 applied to the under side of each strip, so that when the strips pass into the formers the pasted side of the second strip is applied to the outer surface of the inner strip, and, in turn, the pasted side of the outer strip is 90 applied to the outer surface of the intermediate strip so that the outside surface has no exposed pasted sections.

I lay no claim to the particular form of pasting apparatus, as any suitable apparatus may be used without departing from the essential features of the invention.

The formers 7, 8 and 9 are so made and the strips are so fed that the joints of the several strips, forming the tube, will be staggered, as shown in Fig. 8. Then the tube passes through a sizing die 13, shown in Figs. 9 and 10, and from this die to the rolls. 14 is the lower roll housing and 15 is the upper roll housing. The upper roll housing 105 is vertically adjustable and has side guides

16, which are adapted to slideways 17 on standards 18 secured to the lower housing 14, the lower housing being rigidly secured to the base 1. In the standards 18 are vertical screws 19, shown by dotted lines in Fig. 2, which extend through nuts 20 on the upper housing 15. On the upper ends of these screws are beveled gear wheels 21 which mesh with gears 22 on a horizontal shaft 23 mounted in bearings secured to the standards 18.

On the shaft 23 are two hand wheels 24 and 24^a and the shaft is made in two parts and connected by a coupling 25 so that when the parts are coupled by turning either hand wheel the ends of the upper housing can be moved in unison, but, if it be desired to move one end of the housing independently of the other the coupling 25 is released so that, on turning either wheel 24 or 24^a, either end of the housing can be adjusted.

After the paper strips are made into the form of tubes by passing them over the rod 26 connected to the mandrel 27 and through the formers 7, 8 and 9, they pass through a die 13, Figs. 2, 9 and 10, which reduce the tube to about the proper size and also cements the several strips together. The tube then passes between the finishing and pressing rolls 36 and 37 and over the mandrel 27, which is of the proper diameter of the interior of the tube.

The rolls 36 and 37 are alternately arranged, as shown, so as to insure the compacting of the strips or plies of paper and also to bring the tube to the proper cylindrical shape. The rolls 36 are secured to shafts 46 mounted in boxes 35 located either in the lower housing 14, or the upper housing 15 and the rolls 37 are secured on shafts 47 mounted in boxes 35^a either in the lower housing 14 or the upper housing 15, as clearly illustrated in Figs. 2 and 3.

In the present instance, the lower set of shafts is driven from a main shaft 39 on which is a sprocket wheel 41. A chain 41 passes around this wheel and around a wheel 42 on a worm shaft 43 on which are worms 44 meshing with wheels 45. The upper set of shafts is driven from the lower shafts through gearing 48 and 48^a. By the above arrangement of gears, all the rolls are driven at the same speed. Other means of driving the rolls may be resorted to without departing from the main features of the invention.

Each roll 36 has flanges 36^a forming a deep annular groove conforming to one-half of the tube, and each roll 37 is of such width as to pass into the space between the flanges 36^a of the roll 36. The groove in the periphery of the roll 37 is shallow and conforms to one-half of the tube.

It will be noticed that the flanges 36^a of the roller 36 bear upon the hub 30 of the roller 37, so that the rollers are held a proper

distance apart, and when the reduced portion of the mandrel is on a line between the rollers the rollers will not move toward each other and thus reduce the diameter of the tube, as it will be understood that the rollers are in a fixed position at all times in respect to each other and to the tube. By providing the reduced portions on the mandrel, the mandrel is allowed to be retracted by the spring without distorting the tube.

While I have shown one roll bearing upon the hub of the other, it will be understood that the rolls may be spaced apart in any suitable manner so as to prevent the distorting of the tube.

The mandrel 27 over which the tube is formed has a series of reduced portions 29 and tapered shoulders 28 are formed at one end of each reduced portion, as shown in Figs. 4 and 6, and when the shoulders are in line with the rolls, as in Fig. 4, then both the tube and the mandrel are fed forward until the reduced portion of the mandrel is in line with the rolls. Then the mandrel is released and its spring 33 returns it so that the shoulder will be again in line with the rolls, when both the tube and mandrel will again move forward. This action is very rapid, the mandrel having a reciprocating movement while the tube moves forward.

After the tube passes between the last series of rolls, it enters a cylindrical guide 50, which holds the tube in a central position, while it is being cut off to the proper length by the blade 51. This blade is suitably mounted so as to be moved either by hand into the cutting position, or by automatic mechanism tripped by the tube. This latter feature forms no part of the present invention and forms the subject of a separate application filed by me on the 20th day of February, 1918, Serial No. 218,292.

Each of the upper rolls is yieldingly held against the lower rolls by springs 53, which are located upon the boxes for the shafts of the rolls and projections on the upper housing 15. The lower set of rolls can be adjusted vertically by set screws 54, as clearly shown in Fig. 3, and as the upper housing is vertically adjustable it will be seen that the machine can accommodate different sized rolls to manufacture tubes varying in size.

The operation is as follows:

If a three-ply tube is to be formed, then three strips of paper of the proper width are wound upon the reels 3, 4 and 5, and the strips from the reels 4 and 5 pass through the pasting device 10, so as to apply paste, or other cementitious material, to one surface of each of these two strips. The central strip 30 is passed through the former 7, and the strip from the roll 4 is passed through the former 8. The strip from the roll 5 is passed through the former 9. These formers are tapered, as shown, and

bend one strip around another, and the three strips pass over the mandrel and through the sizing die 13, which tends to press the sheets together and initially to 5 form the tube. It will be noticed that the joint of one strip is out of line with another, as clearly shown in Fig. 8, and this is accomplished by feeding the first central strip so that its joint will be at the top. Then the 10 strip from the reel 4 is fed so that the joint will come to the right hand side and the other strip from the reel 5 will come to the left hand side, as the present tube is a three-ply tube. If more plies are used, then 15 additional reels are provided, as well as additional formers. After this the tube passes between the first pair of rollers 36 and 37 and then between the balance of the series of 20 rolls. These rolls are driven continuously and the tube is intermittently fed forward, while the mandrel, on which the tube is formed, is reciprocated.

As before remarked, the mandrel has a series of reduced portions and tapered 25 shoulders are formed at one or both ends of said portions so that as the rolls rotate constantly in one direction the tube is pinched between a shoulder of the mandrel and the rolls, as shown in Fig. 4, and both 30 the mandrel and the tube will move in the direction of the arrow *a* in said figure. As soon as the reduced portion of the mandrel is opposite to the pinching point of the rolls, the mandrel is released and its spring 33 35 moves it in the opposite direction, as indicated by the arrow *b*, until the shoulder is again brought into alignment with the centers of the two rolls, when the tube is again pinched and the mandrel and tube are 40 again moved forward in the direction of the arrow. Then the reduced portion of the mandrel is again brought in alignment with the center line of the rolls and the tube either remains stationary or is moved 45 slightly forward, while the mandrel is again retracted. This is repeated so that the tube has a very rapid intermittent forward movement, while the mandrel has a very rapid short reciprocating movement. This intermediate pinching of the tube brings the several layers close together and makes the 50 paste adhere firmly to the sections. By having a series of rolls, it insures the pinching of the entire surface of the tube, as the surface, which would be missed by one roll, is pinched by the second, third and fourth roll. There may be as many of these rolls as desired.

In small tubes, and in three-ply tubes, 55 four rolls would be necessary for the purpose, but for the larger tubes the number of rolls may be increased. In some cases, the number of rolls may be reduced.

In some instances, it may be desirable to 60 locate a pair of horizontally arranged rolls,

as indicated by dotted lines in Fig. 2, at the end of a train of vertically arranged rolls in the manufacture of some types of tubes, but in the manufacture of ordinary types of tubes, this horizontal roll is not 70 essential.

By making each pair of rolls in the manner shown in Figs. 4 and 5, where the flangeless roll 37 extends into the flanged roll 36, the opening between the rolls is 75 closed at the edges so as to prevent the escape of pulp, or paste, which might ooze out of the tube, as it is being squeezed.

It will be noticed that the sharp edges of the rolls 37 fit snugly against the curved portion of the flanged rolls and, as these edges are comparatively sharp, no fins or other projections, are formed on the finished tube.

It will be seen by the above construction and operation that I can make a tube of the 85 type in which the seams are arranged longitudinally and in which the tubes are brought to a proper size, being made in continuous lengths, which can be cut off so as to produce tubes of any length desired and this is 90 accomplished without interfering with the forward movement of the tube.

I claim:

1. The combination in a tube forming machine, of means for forming the tube; a 95 pair of grooved rolls adapted to conform to the shape of the tube; a mandrel having a reduced portion and a shoulder over which the tube passes from the forming means; means for continuously driving the pair of 100 rolls in one direction; and a spring tending to move the mandrel in the opposite direction, so that the tube passing through the machine will be moved intermittently forward and the mandrel will be reciprocated. 105

2. The combination in a tube forming machine, of a series of formers through which strips of paper are passed to initially form a tube; a series of rolls; means for driving the rolls continuously in one direction; a 110 mandrel extending between the rolls of the series, said mandrel having reduced portions and tapered shoulders; a spring for retracting the mandrel so that as the tube passes between the rolls and over the mandrel it is pinched between the rolls and the shoulders on the mandrel, the tube and the mandrel being carried forward until the reduced portions of the mandrel are opposite the center line of the rolls when the mandrel is released and is retracted so that the tube has an intermittent forward movement, while the mandrel has a short reciprocating movement. 115

3. The combination in a tube forming machine, of a series of formers; a die through which the formed tube passes; a mandrel having a rod extending through the die and through the formers; a spring on the rod arranged to retract the mandrel, said man- 120 125

130

drel having reduced portions with inclined shoulders; a series of rolls through which the mandrel extends so that when the tube is formed and passes into the die and over the mandrel and between the rolls, it will be intermittently pressed and moved forward, while the mandrel will have a short reciprocating movement.

4. The combination in a machine for making paper tubes, of means for forming the tube; a mandrel and a pair of pressing rolls between which the mandrel and the tube extend, one of said rolls having a deep flange and having a bearing portion conforming to one-half of the tube, the other roll being narrow and adapted to extend into the space between the flanges of the other roll and having a groove in its periphery conforming to the other half of the tube.

5. The combination in a paper tube forming machine, of a pair of rolls, one roll having a flange and a semi-circular groove, the other having a semi-circular groove in its periphery and arranged to extend between the flanges of the first mentioned roll, the flanges of one roll bearing against the hub of the other roll so as to keep the rolls spaced a given distance apart; and a mandrel having a reduced portion; means for retracting the mandrel; and means for driving the roll so that the tube will be fed forward and the mandrel will have a reciprocating motion.

6. The combination in a tube forming machine, of means for forming a tube; a mandrel over which the tube extends; a pair of rolls for pressing the tube onto the mandrel, said rolls being geared together; a worm shaft; a worm thereon; a worm wheel on one of the roll shafts; and means for retracting the mandrel after it has been fed forward a given distance by the roll, pinching the tube on the mandrel.

7. The combination in a tube forming machine, of three rolls on which the strips of paper to form the tube are wound; a pasting device through which two of said strips extend so as to paste one side of each strip; an independent former for each strip; a die through which the formed tube extends; a mandrel on which the tube is pressed; a series of grooved rolls through which the tube and the mandrel extend; means tending to retract the mandrel, said mandrel having shoulders between which and the rolls the tube is gripped to move the tube and the mandrel forward, and when the reduced portion of the tube is in line with the rolls the mandrel will be released and will be retracted; and a cylindrical guide beyond the last pair of rolls into which the tube extends, said guides centering the tube so that it can be severed by a cutting off device.

In witness whereof I affix my signature.

OTTO HERMAN ROESSLING.
